UNITED STATES PATENT OFFICE

CARL G. ZIRNKILTON, OF PHILADELPHIA, PENNSYLVANIA

METHOD OF REPRESENTING DESIGNS

Application filed June 18, 1931. Serial No. 545,332.

This invention relates to a new and desirable method for presenting and displaying original or other designs for articles of jewelry on approval to prospective purchasers and more particularly for use by wholesale merchants and designers in showing said designs to purchasers of the retail house class.

A particular feature of the invention is to provide means affording an adequate representation of an article of jewelry which more effectively and realistically portrays the design thereof to purchasers.

Further features and details in the formation of the medium of presentation are disclosed hereinafter and shown in the accompanying drawing, in which:

Figure 1 is a view in elevation showing the outline of an article of jewelry sketched on a suitable background such as celluloid;

Fig. 2 is a view in perspective, showing the outline of the article subsequent to the embossing thereof from the reverse side of the backing;

Fig. 3 is a view in section on line 3—3 of Fig. 2;

Fig. 4 is a view in elevation showing the sheet of material with the modeled article disclosed in Fig. 3 cut therefrom;

Fig. 5 is a view in elevation of the embossed ring after it has been cut out from the sheet of material; and

Fig. 6 is a view in elevation showing the completed article for presenting articles of jewelry for approval.

In proceeding in accordance with my invention, I may first, as shown in Fig. 1, sketch the design of the article to be represented in pencil on a suitable piece of celluloid having a thickness say of approximately one one-hundredth of an inch. The piece of celluloid with the article depicted on one face thereof is then laid face downward upon a resilient base. The base may be suitably composed of a piece of relatively thick, soft rubber and preferably, in placing the celluloid sheet upon said resilient base, the face of the said sheet having the sketch of the article thereon is placed in contact with the surface of the base, the reverse side thereof thus being free for embossing purposes.

The celluloid is now modeled or embossed from the exposed reverse side by rounded steel or other suitable burnishing tools variously sized to permit bringing out even the most minute features in the design of the article to be represented as shown in Figs. 2 and 3 of the drawing. By embossing the design of the article on the celluloid sheet in this manner, the depiction thereof is offset from the plane of the remainder of the sheet and appears in relief. This modeled or relief representation of jewelry is then cut from the celluloid sheet by scissors or other suitable cutting means as disclosed in Fig. 5 and is subsequently subjected to a thorough sand blasting or equivalent operation over its entire surface.

When the above blasting operation is completed, the embossed celluloid representation is secured on a neat card board mat or other backing element and convexly with respect thereto as shown in Fig. 6, in any suitable manner such as by glue, and is then artistically painted or tinted with pigments or dyes to show all the details of the design. The mat may be further finished with a card board frame or border.

It will be noted that the representation of articles of jewelry for approval by the method herein outlined, I provide such a method that effectively and in a more realistic manner depicts articles of this character. The presentation resulting from the herein described method is better adapted to represent articles of jewelry than methods used heretofore which, for the most part, have consisted in mere representative depictions thereof in a horizontal plane and which do not produce the desirable perspective effect which is afforded by my invention.

While I have set forth the embodiment of my invention for the purpose of description, it will be apparent that certain modifications and changes may be made therein except as limited in the appended claims.

I claim:

1. The herein described method of representing articles of jewelry consisting of embossing a desired design in a piece of workable material, cutting said embossed design

from the material, subjecting said design to a thorough sand blasting, mounting the embossed design upon a backing convexly with respect thereto, and subsequently coloring the depiction to represent the embossed article as desired.

2. The herein described method of representing articles of jewelry consisting of sketching the design thereof on sheets of 10 relatively thin celluloid, embossing the said design from the reverse side of the celluloid sheet on a soft resilient support by means of variously sized embossing tools, cutting the embossed depiction from the celluloid 15 sheet and subjecting said depiction to a thorough sand blasting over the entire surface thereof, mounting the celluloid representation on a suitable backing element convexly with respect thereto, and subsequently 20 coloring the depiction to represent the article as desired.

3. The herein described method of representing a product consisting of embossing a desired design on a piece of workable material, 25 subjecting said design to a thorough sand blasting and mounting the embossed design on a backing convexly with respect thereto.

4. The herein described method of representing a product consisting of embossing a 30 desired design on a piece of workable material, cutting said embossed design from the material, subjecting said design to a thorough sand blasting, and mounting the embossed design on a backing convexly with 35 respect thereto.

5. The herein described method of representing a product consisting of sketching the design thereof on sheets of relatively thin celluloid, embossing the said design on a soft, 40 resilient spot by means of various sized embossing tools, cutting the embossed depiction from the celluloid sheet and subjecting said depiction to a thorough sand blasting over the entire surface thereof, and mounting the celluloid representation on a suitable 45 backing element convexly with respect thereto.

6. The herein described method of representing articles of jewelry consisting of 50 sketching the design thereof on sheets of relatively thin celluloid, embossing the said design from the reverse side of the celluloid sheet on a soft resilient support by means of variously sized embossing tools, cutting said 55 depiction to a thorough sand blasting over the entire surface thereof, and mounting the celluloid representation on a suitable backing element convexly with respect thereto.

7. The herein described method of representing articles of jewelry consisting of 60 sketching the design thereof on sheets of relatively thin celluloid, embossing the said design from the reverse side of the celluloid sheet on a soft resilient support by means of variously sized embossing tools, cutting the 65

embossed depiction from the celluloid sheet, subjecting said depiction to a thorough sand blasting over the entire surface thereof, and subsequently coloring the depiction to represent the article as desired.

8. The herein described method of representing articles of jewelry consisting of embossing a desired design in a piece of workable material, cutting said embossed design from the material, subjecting said design to a thorough sand blasting, and subsequently 75 coloring the depiction to represent the embossed article as desired.

CARL G. ZIRNKILTON.
